US0D1000280S

(12) **United States Design Patent** (10) Patent No.: **US D1,000,280 S**
(45) Date of Patent: ** *Oct. 3, 2023

(54) **CONTAINER**

(71) Applicant: **Conopco, Inc.**, Englewood Cliffs, NJ (US)

(72) Inventors: **Gregory Lalier**, Brookfield, CT (US); **Mary Margaret Sheridan**, Stamford, CT (US); **Daniel Martin**, Naugatuck, CT (US); **Wooyeon Cho**, Trumbull, CT (US); **Heesop Chong**, New York, NY (US); **Mariana Escobar Jimenez**, New York, NY (US); **Michelle C Mak**, New York, NY (US); **Laurent Jean-Marie Hainaut**, New York, NY (US)

(73) Assignee: **Conopco, Inc.**, Englewood Cliffs, NJ (US)

(*) Notice: This patent is subject to a terminal disclaimer.

(**) Term: **15 Years**

(21) Appl. No.: **29/761,169**

(22) Filed: **Dec. 7, 2020**

(51) LOC (14) Cl. **09-01**
(52) U.S. Cl.

USPC **D9/529**; D9/549

(74) Attorney, Agent, or Firm — Gerard J. McGowan, Jr.

(57) **CLAIM**

The ornamental design for a container, as shown and described.

DESCRIPTION

FIG. 1 is a top, side perspective view of a container showing our new design;

FIG. 2 is a front elevational view;

FIG. 3 is a rear elevational view;

FIG. 4 is a side elevational view from the left side;

FIG. 5 is an elevational view of the other side;

FIG. 6 is a top plan view; and,

FIG. 7 is a bottom plan view.

The broken lines in the drawings depict portions of the container that form no part of the claimed design.
